UNITED STATES PATENT OFFICE.

GEORGE L. ROBERTSON, OF PHILADELPHIA, PENNSYLVANIA, ASSIGNOR OF ONE-HALF
TO JOSHUA R. RITCHIE, OF PHILADELPHIA, PENNSYLVANIA.

PNEUMATIC HAMMER.

1,048,099.

Specification of Letters Patent. Patented Dec. 24, 1912.

Application filed August 23, 1912. Serial No. 716,600.

To all whom it may concern:

Be it known that I, GEORGE L. ROBERTSON, a citizen of the United States, residing at Philadelphia, in the county of Philadelphia and State of Pennsylvania, have invented 5 certain new and useful Improvements in Pneumatic Hammers, of which the following is a specification.

My invention relates to improvements in 10 pneumatic hammers, the object of the invention being to provide a pneumatic hammer which is so constructed that vibrations of the hammer are not transmitted to the operator holding the hammer, but are absorbed 15 within the hammer.

A further object is to provide a pneumatic hammer having a movable barrel cushioned by means of a spring within a jacket and guiding the movement of a plunger so that 20 the vibrations caused by the latter are imparted to the barrel, and are absorbed by the cushioning means therefor, and do not reach the operator holding the hammer.

With these and other objects in view, the 25 invention consists in certain novel features of construction and combinations and arrangements of parts as will be more fully hereinafter described and pointed out in the claims.

30 In the accompanying drawings: Figure 1 is a view in longitudinal section illustrating my improvements. Fig. 2 is a view in cross section on the line 2—2 of Fig. 1, and Fig. 3 is a view in cross-section on the line 3—3 of Fig. 1.

1 represents a metal jacket which is cylindrical in form throughout the greater portion of its length, but at one end is tapered or made conical as shown at 2 and is provided with a screw-threaded opening 3 in its end to receive the shank 5 of the set 6. The shank 5 is screwed tightly into the end of the jacket, and projects inwardly into the cylindrical bore 7 of my improved barrel 8. 40 This barrel 8 fits within the jacket, but is free to slide longitudinally therein. The opposite end of the jacket is enlarged in diameter as shown at 9, and is internally screw-threaded engaging external screw-threads on a cylindrical casing 10. This casing 10 is integral with a handle 11 having a passage 12 therethrough for the air, and a valve 13 controlling the flow of air.

The passage 12 discharges into the end of casing 10 and in this casing a piston 14 is

mounted to slide. This piston 14 is fixed to the valve box 15 and the latter located at the end of barrel 8. The barrel 8 is provided with passages 16 for the air to compel the reciprocation of the plunger 17 which snugly fits within the bore of the barrel and strikes the shank 5 of set 6 when operated. The inner end of the barrel bore is closed by a perforated integral partition 8^a which compels the barrel to move when the plunger 17 moves inwardly.

The valve box 15 is provided with a suitable valve (not shown) controlling the passage of air through the several ports therein and through the passages 16, and this box is connected to the end of the barrel by means of dowels 18 to maintain the passages in alinement. Ports 19 are provided in the jacket at the point where said jacket increases in diameter, so that the air is free to 75 escape after passing through ports 20 in the valve box. It is to be understood that the piston 14 has a central passage 21, so that the air from passage 12 is free to flow into the center of the valve box, and I do 80 not limit myself to any particular construction of valves, one arrangement of passages controlling the operation of the plunger, as my improvements are applicable with any structures capable of performing this function. Between the piston 14 and the end of casing 10, a coiled spring 22 is located and exerts pressure on the piston tending always to project the barrel 8 against the conical 85 end of jacket 1.

In operation, the set 6 is positioned against the rivet and while tightly pressed thereagainst, the valve 13 is operated to admit the air and the plunger 17 reciprocates in the barrel and strikes the shank 5 of the set. 90 The vibration caused by this impact and by the movement of the plunger causes the barrel 18 to move longitudinally within the jacket, and this movement is absorbed by the spring 22 preventing transmission of 95 such vibration to the jacket and to the handle. The spring therefore acts as a shock absorber and the tension of this spring may be adjusted by screwing the jacket onto the casing 10. When the proper tension is had, 100 the parts are locked by a jam nut 23 as clearly shown in Fig. 1.

Various slight changes might be made in the general form and arrangement of parts described without departing from my in- 110

vention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A pneumatic hammer comprising a jacket, a reciprocating plunger in the jacket, means within the jacket controlling the movement of the plunger, and shock absorbing means within the jacket absorbing the vibrations caused by the plunger, substantially as described.
2. A pneumatic hammer comprising a jacket, a tool located in one end of the jacket, a barrel movable in the jacket, a plunger in the barrel, and elastic means cushioning the movement of the barrel, substantially as described.
3. A pneumatic hammer comprising a jacket, a tool located in one end of the jacket having a shank projecting into the jacket, a barrel mounted to move longitudinally in the jacket and having a central bore receiving the shank of the tool, a plunger mounted to reciprocate in the barrel, and a spring exerting pressure against one end of the barrel, substantially as described.
4. A pneumatic hammer comprising a jacket, a tool located in one end of the jacket, a barrel movable in the jacket, a plunger in the barrel, elastic means cushioning the movement of the barrel, a valve box located at one end of the barrel, a piston on said valve box, and a spring bearing against said piston, substantially as described.
5. A pneumatic hammer comprising a jacket, a tool located in one end of the jacket having a shank projecting into the jacket, a barrel mounted to move longitudinally in the jacket and having a central bore receiving the shank of the tool, a plunger mounted to reciprocate in the barrel, a spring exerting pressure against one end of the barrel, a valve box located at one end of the barrel, a piston on said valve box, and a spring bearing against said piston, substantially as described.
6. A pneumatic hammer comprising a jacket, a tool fixed in one end of the jacket, the other end of said jacket enlarged trans-

versely and internally screw-threaded, a handle having an integral cylindrical externally screw-threaded casing screwed into the enlarged end of the jacket, a barrel in the jacket, a plunger mounted to move in the barrel, a valve box against one end of the barrel, a piston against the valve box, and cushioning means between the piston and the end of the cylinder, substantially as described.

7. A pneumatic hammer comprising a jacket, a tool fixed in one end of the jacket, the other end of said jacket enlarged transversely and internally screw-threaded, a handle having an integral cylindrical externally screw-threaded casing screwed into the enlarged end of the jacket, a barrel in the jacket, a plunger mounted to move in the barrel, a valve box against one end of the barrel, a piston against the valve box, said piston fitting snugly within the casing and having a central opening, said handle having an air passage communicating with the end of the casing, and a coiled spring in the casing between the end of the casing and the piston, substantially as described.

8. A pneumatic hammer comprising a jacket having a reduced conical end and having an enlarged end, both ends internally screw-threaded, a tool having a shank screwed into the conical end of the jacket, a barrel fitting the smaller diameter of the jacket and having a central longitudinal bore receiving the end of the shank, a plunger mounted to reciprocate in the bore of the barrel, a valve box located against the end of the barrel, a piston fixed to the valve box and having a central opening therein, a cylindrical casing externally screw-threaded and screwed into the larger end of the jacket and receiving the piston therein, a jam nut on said casing against the end of the jacket, a coiled spring in the casing bearing against the piston, and means for directing air into the end of the casing, substantially as described.

In testimony whereof I have signed my name to this specification in the presence of two subscribing witnesses.

GEORGE L. ROBERTSON.
